Application December 5, 1935, Serial No. 52,947
Renewed March 6, 1937

25 Claims. (Cl. 74—6)

This invention relates to apparatus for starting internal combustion engines.

The objects of the invention are chiefly to provide an engine starter which is efficient, durable and quiet in operation and which is economical to construct. According to the disclosed embodiment of my invention these objects are accomplished by providing a friction drive between the engine to be started and the starting motor, said drive comprising a disc or annular flange associated with the engine fly-wheel or other member connected with the engine crank shaft and a pair of driving discs which are engageable with opposite faces of the driven disc. Each driving disc has an independent driving connection with the starting motor shaft. Each of said independent driving connections includes camming members so constructed and arranged that when a driving disc has been brought into engagement with the driven disc, rotation of the motor shaft will force the driving disc against the driven disc with pressure sufficient for driving engagement between the motor and driven disc whereby the motor will crank the engine. Said independent driving connection is so constructed that, when the engine becomes self operative, the driving pressure will be relieved to release the engine from the starting motor so that the engine will not drive the motor at an excessive speed.

The present invention includes means operating independent of the motor for causing the driving discs to engage the driven disc before the motor operates. As will be more apparent hereinafter, the shock or abnormal strain attendant upon establishment of connections between the starting motor and the engine has been minimized, and, consequently, the operation of the starter drive mechanism has been made more quiet, so that the durability as well as reliability of the starter drive mechanism has been greatly improved.

Further objects and advantages of the present invention will be apparent from the following description, reference being had to the accompanying drawings wherein a preferred embodiment of one form of the present invention is clearly shown.

In the drawings:

50 Fig. 1 is a side view partly in section showing a preferred embodiment of the invention in its normal condition.

Fig. 2 is a wiring diagram thereof.

Fig. 3 is a fragmentary longitudinal sectional view of a starting apparatus.

Figs. 4, 5, 6 and 7 are sectional views taken respectively on the line 4—4, 5—5, 6—6 and 7—7 of Fig. 3.

Figs. 8, 9 and 10 are diagrammatic views similar to Fig. 3 but showing the mechanism in different positions of operation.

The motor 20 for starting the internal combustion engine is preferably an electric motor comprising field frame 21 associated with an end frame 22 and a housing 23 which carry bearings 10 24 and 25, respectively, for the motor armature shaft 26 which carries an armature 27.

Referring now particularly to Figs. 3 to 7 the shaft 26 carries a tubular shaft 30 which is splined at 31 to the shaft 26 so that the tubular 15 shaft 30 is at all times drivingly connected with the shaft 26 but may slide thereon to a limited extent. The tubular shaft 30 is urged against the end of the bearing 25 by spring 32 which surrounds the armature shaft 26 and which is 20 located between the armature 27 and the left hand end of the tubular shaft 30.

The shaft 30 carries driving disc 33 and driving disc 34 adapted to move into engagement with and to drive a driven disc 35 connected 25 with the engine to be started. Each of the driving discs 33, 34 has an independent driving connection with the shaft 30 said driving connection being so constructed and arranged that, after the driving discs have been moved against 30 the driven disc 35, rotation of the shaft 30 by the motor will cause the driving disc to be pressed against the driven disc with pressure sufficient for engine starting purposes and that, after the engine has become self operative, the pressure 35 between the driving discs and driven disc will be relieved so that the engine will not drive the starting motor while the engine is self operative. Each of these driving connections between the driving discs and motor shaft 30 comprises camming members, preferably cooperating screw threads, externally on the shaft 30 and internally on the driving discs. The driving disc 33 is connected with the shaft 30 through a double screw thread 36 and normally rests against a 45 collar 37 secured to the shaft 30. The driving disc 34 is connected with shaft 30 through a screw thread connection which is provided by a plurality of balls 38 occupying mating helical grooves 39 and 40 provided respectively by the 50 shaft 30 and the tubular extension of driving disc 34. It will be noted that the screw thread connections between the driving discs and the shaft 30 are opposite in pitch so that, after these 55 discs have been moved into engagement with the

driven disc 35 rotation of the motor shaft 30 will cause each driving disc to be wedged independently against the driven disc with a pressure sufficient for engine starting purposes, and 5 so that, after the engine becomes self operative and the driven disc 35 attempts to rotate the driving discs 33 and 34 faster than they can be rotated by the starting motor, the driving pressure between the driving discs and the driven 10 disc will be relieved so that the engine cannot drive the starting motor at excessive speed.

The present invention includes a means independent of the starting motor for causing the driving discs 33, and 34 to be moved into engagement with the driven disc 35 before the starting motor operates to cause the driving discs to be wedged against the driven disc with pressure sufficient to transmit torque sufficient for engine starting purposes. This means for 20 causing a preliminary engagement of the driving discs with the driven disc will now be described.

The disc 34 has its tubular extension provided exteriorly with a plurality of helical splines 41 adapted to be engaged by the internally splined flange 42 of a sleeve 43 which is supported by a disc 44 riveted to the left hand end of shaft 30. Disc 44 has tongues 47 received by a longitudinal groove 48 of sleeve 43. A spring 45 is 30 located between the disc 44 and the flange 42 and tends to maintain the relative location of the sleeve 43 and disc 34 as shown in Fig. 3, that is, with the tongues 47 bearing against the left hand ends of grooves 48. The sleeve 43 being 35 longitudinally splined to the hub of the driving disc 34, due to the great mass of parts connected with the shaft 30 including the armature shaft 26 and the armature 27, the shaft 30 tends to remain stationary as the sleeve 43 is moved longitudinally. Hence, the sleeve 43 moves longitudinally without rotating substantially. The pitch of the splines 41 formed on the sleeve like extension 40 of disc 34 is such that, as the sleeve 43 is moved toward the left from its position shown in Fig. 3 the disc 34 will rotate relative to the shaft 30 in a direction such as to cause the disc 34 to move into engagement with the disc 35.

In order that the sleeve 43 may be moved toward the left from its position shown in Fig. 3 it is provided with an external flange 49 for receiving the ends 50 of a bifurcated lever 70 having at its upper end an elongated notch 71 which receives a pin 72 carried by bifurcated bracket 73 55 integral with an L-shaped bracket 74 attached to an electromagnet frame 75 mounted upon the motor frame 21. A spring 76 surrounds a stud 77 attached to the bracket 73 and urges the upper end of the lever 70 against the pin 72.

60 The lever 70 is actuated electromagnetically by means which will now be described with reference to Fig. 2. As shown diagrammatically in Fig. 2, magnet frame 75 encloses electromagnet windings 80 and 81 surrounding a movable solenoid 65 armature 82 guided by the magnet frame 75 for sliding movement toward a stationary core 83 which is located in the magnetic circuit of the electromagnet. The armature 82 is connected by a link 84 with the lever 70. Armature 82 is associated with a rod 85 upon which is mounted a non-conducting collar 86 yielding urged by spring 87 against a shoulder 88, the spring 87 being confined between the collar 86 and a washer 89 held from moving toward the right by a pin 90. 70 A spring 91 located between a stationary part

92 and the rod 85 normally maintains the rod 85 and the armature 82 in the normal position as shown in Fig. 2.

The collar 86 carries a movable switch contact 95 adapted to engage with contacts 96 and 97 5 of the starting motor switch. Contact 96 is connected by wire 98 with a switch terminal 99. Contact 97 is connected with the starting motor 20 which is grounded at 100. Terminal 99 is connected with storage battery 101 grounded at 102. Terminal 99 may be connected simultaneously 10 with terminals 103 and 104 by a movable contact 105. Terminal 104 is connected with contact 106 of an automatic switch having also a terminal 107 connected with windings 80 and 81, 81 being 15 connected with contact 97 and 80 being grounded at 108. This automatic switch designated in its entirety by numeral 110, comprises a suction chamber 111 connected by pipe 112 with the intake manifold of an internal combustion engine. 20 One wall of the chamber 111 is provided by a diaphragm 113 which is attached to switch contact 114, said contact being normally in engagement with contacts 106 and 107, said engagement being effected through the action of a spring 115 25 located so as to press the diaphragm 113 downwardly as viewed in Fig. 2.

As stated before, this invention embraces the feature of causing the driving discs 33 and 34 to be moved into engagement with the driven disc 35 before operating the starting motor 20. This is accomplished by means independent of the motor, namely, the electromagnet means shown diagrammatically in Fig. 2. The manner in which the driving discs are caused to engage the driven 35 discs will now be described particularly with respect to Figs. 8, 9 and 10.

To start the engine the operator turns the switch contact 105 so as to cause it to engage the contact 103 and the contact 104. The ignition is then turned on, the ignition circuit being connected with the terminal 103 which is then connected with the battery 101. The terminal 104 being then also connected with battery 101, current will flow from the battery 101 45 through the windings 80 and 81, the former being directly grounded at 108 and the latter being indirectly grounded through the motor 20. The electromagnet windings 80 and 81 being energized, the armature 82 will move toward the left 50 thereby causing the lever 70 to move to swing toward the left in a clock-wise direction around its pivot 72. During the movement of the lever 70 the contact 95 will be moving toward contacts 96 and 97; but before engagement of these contacts actually occurs, the driving discs 33 and 34 will be brought into engagement with the driven disc 35 in a manner which will be apparent from a consideration of Figs. 8, 9 and 10.

As lever 70 moves toward the left the entire drive assembly will be moved bodily toward the left from the position shown in Fig. 8 to that shown in Fig. 9 thereby causing the driving disc 33 to engage the driven disc 35. This movement of the drive assembly is resisted by the spring 82 65 which normally holds the shaft 30 against the bearing 25.

Further movement of the lever 70 toward the left causes the sleeve 43 to move to the left relative to the driving disc sleeve 40 thereby causing 70 the driving disc 34 to be rotated in such direction relative to the shaft 30 that the disc 34 will be moved from its position shown in Fig. 9 to that shown in Fig. 10 wherein said disc 34 engages the driving disc 35. The driving discs 75

have now completed their preliminary movements into engagement with the driven discs. Hence the starter drive has been pre-conditioned for operation by the electric motor. After the driving discs have completed their preliminary movement the lower end of the lever 10 cannot move any further toward the left.

Continued motion of the solenoid armature 82 toward the left to close contacts 95, 96 and 97 may take place by reason of the fact that there is lost motion between the upper end of the lever 10 and the pivot bearing 12. Just before these contacts are closed, the spring 16 is held by the solenoid armature 82 under compression, so that yielding pressure is applied between end 50 of lever 10 and the sleeve flange 44. Therefore, it is only after the driving discs have been brought into engagement with the driven discs under yielding pressure that the motor switch contact 20 is caused to engage the stationary contacts 96 and 97. When this occurs the motor 20 operates to turn the shaft 26. The winding 81 is then short circuited and winding 80 only is effective to hold the motor switch closed. Winding 80 comprises preferably a large number of turns of fine wire and winding 81 fewer turns of coarser wire. Both windings are required to effect movement of the armature 82 initially toward the core 83 but winding 80 only is required to maintain the armature 82 in its attracted position. The starting motor then will operate to cause the shaft 26 to rotate in a clockwise direction as viewed looking in the direction of arrow 60 of Fig. 8. At the instant the motor starts to turn the shaft 26, the driving discs 33 and 34 being then in engagement with the driven disc 35, the first action is to increase the pressure between the driving discs and the driven discs due to the cooperation of the screw thread connections between the driving discs and the motor shaft.

Thus in response to the operation of the electric motor in turning the shaft 26 the driving discs 33 and 34 are caused to press against the driven disc 35 with pressure sufficient to insure a driving engagement between the electric motor and the engine for engine starting purposes. Hence the electric motor is drivingly connected with the engine and will start the latter. This driving engagement has been effected noiselessly due to the fact that means independent of the motor have been employed for moving the driving discs against the driven disc before the motor is connected with the current source. Then when the motor is caused to operate it produces noiselessly a pressure between the driving and driven discs sufficient for engine starting purposes.

When the engine becomes self operative and attains a speed such that the linear speed of the driven disc 35 as effected by the engine exceeds the linear speed of the driving discs 33 and 34 as effected by the starting motor, driving engagement between the driving and driven discs of the starter drive is automatically released. This is accomplished due to the fact that as the driven disc 35 tends to run ahead of the driving discs 33 and 34 these driving discs tend to screw themselves along their screw threaded connections away from the driven discs. After the engine starts the electromagnetic is automatically deenergized by the opening of the automatic switch 110. The suction produced in the engine intake when operating will be sufficient to raise the diaphragm 113 against the action of the spring 115, thereby separating contact 114 from contacts 106 and 107. The spring 91 will then

be released to effect movement of the parts 85, 82, 84 and 10 toward the right as viewed in Fig. 2. The spring 16 will also be released so as to move the upper end of the lever 10 toward the right returning it to its normal position. In this way 5 the engine starter drive parts are restored to normal position as shown in Figs. 1, 2, 3 and 8.

The ends 50 of lever 10 bear yieldingly upon the sleeve flange 49 and the internal flange 42 of sleeve 43 will bear yieldingly against the 10 helical splines 41 of the tubular extension of driving disc 34. Therefore, since the sleeve 43 is yieldingly urged toward the left the driving disc 33 will be yieldingly urged against the driven disc 35; and, since the driving disc 34 is caused 15 to rotate by the sleeve 43 under the action of yielding pressure, the driving disc 34 will be yieldingly pressed against the driven disc 35. Therefore both driving discs are urged by means independent of the motor against the driven disc 20 with yielding pressure. This is desirable for the purpose of compensating for wear of the friction surfaces of the driving and driven discs. There is another purpose which is important. If the engine should make a weak or false start and fail 25 to attain a speed sufficient to insure self operation, the spring 16, being then held under pressure greater than normal by the electromagnet, an actuating force is thereby stored in the spring 16 which tends to maintain the preliminary contact between the driving discs and the driven disc so that, if there is any tendency to relieve pressure between the driving and driven discs during a false or weak start of the engine, this 30 tendency will be counteracted by the tendency 35 of the spring 16 to urge the driving discs almost instantaneously back into cooperative relation with the driven discs. In other words, the spring 16 forms a function analogous to that performed 40 in the conventional one way or overrunning clutch by the springs which are provided each for urging a clutch roller into wedging engagement between the clutch cam and the clutch shell. Thus when the engine attempts to start on its own power and tends to release the driving 45 engagement between the driving and driven discs and then fails to attain a speed sufficient to maintain self operation, the starting motor drive is at all times ready to pick up the load of cranking 50 the engine instantaneously.

The electromagnetic means which operates independent of the motor to cause the driving discs to be pressed against the driven discs before the motor is operated is not only a convenient means for preconditioning the starter drive but is one 55 which is well adapted to cooperate with the starter drive of this type. It requires a relatively small force to move the driving disc 33 from its position shown in Fig. 8 to that shown in Fig. 9 where it engages the driven disc 35 and 60 it requires a substantially greater force to move the driving disc 34 into engagement with the driven disc 35 and to effect compression of spring 16 beyond its normal state of compression. The electromagnetic device is well adapted 65 to provide the actuating forces which are required. At first the attraction upon the solenoid armature 82 is relatively small but the force required to move the driving disc 33 toward the left is relatively small. As the solenoid 70 armature 82 approaches the core 83 the attraction increases greatly to give the necessarily greater force required to move the driving disc 34 against the driven disc 35 and to compress the spring 16 beyond its initial state. It is also 75

necessary that the starter switch contact 95 be pressed against the stationary contacts 96 and 97 with a pressure sufficient to insure a good electrical contact. The electromagnet is also well adapted to give this final pressure which is needed between the starter contacts in the starter switch. During final movement of the solenoid armature 82 toward the left when the air gap between the armature and core is closing up the pull upon the armature increases tremendously and is sufficient not only to effect the desired movements of the engine starter drive but also to compress the spring 87 beyond its initial state of compression and to force movable contact 95 firmly against the stationary contacts 96 and 97.

The electromagnet is so constructed as to effect a pull on the armature 82 sufficient to make good electrical contact between the contacts in the starter switch. The magnetic pull required for closing the switch properly is greater than that sufficient for preconditioning the engine starter drive prior to actual operation of the motor.

25 As undue pressure between the driving discs and the driven disc prior to operation of the motor is as undesirable as insufficient pressure the spring 76 operates while the motor switch is closed to limit the force which can be applied by the electromagnet to the shifting lever 10. The spring 76 is so designed that upon being deflected a certain distance by the armature 82 when closing the motor switch the spring will exert the proper force upon the lever 10 tending 30 to rotate it clockwise about its pivotal connection with the link 84. In this way the spring 76 operates not only as a spring exerting yielding pressure upon the shifting collar flange 49 for the purposes herein specified but spring 76 operates 35 also as a means for limiting the amount of pressure which can be effected by the electromagnet.

40 While the embodiment of the present invention as herein disclosed, constitutes a preferred form, it is to be understood that other forms 45 might be adopted, all coming within the scope of the claims which follow.

What is claimed is as follows:

1. In an engine starter, the combination of a driven disc connected with the engine, driving discs located respectively on opposite sides of the driven disc, a starting motor, a shaft driven by the motor, means independent of the motor for moving the driving discs against the driven disc prior to operation of the motor, and independent 50 driving connections between the shaft and driving discs, said connections each including camming members whereby, in response to operation of the motor after operation of said independent disc moving means, each driving disc is urged against the driven disc with pressure sufficient for driving engagement, and whereby, when the engine becomes self-operative, the driving pressure will be relieved.

2. In an engine starter, the combination of a driven disc connected with the engine, driving discs located respectively on opposite sides of the driven disc, a starting motor, a shaft driven by the motor, means independent of the motor for moving the driving discs against the driven disc 55 prior to operation of the motor, and independent driving connections between the shaft and driving discs, each of said independent connections being so constructed and arranged that, in response to operation of the motor after operation of said independent disc moving means, the pres-

sure between each driving disc and the driven disc will be increased and that said pressure will be relieved when the engine becomes self-operative.

3. In an engine starter, the combination of a driven disc connected with the engine, driving discs located respectively on opposite sides of the driven disc, a starting motor, a shaft driven by the motor, means independent of the motor for moving the driving discs against the driven disc prior to operation of the motor, and independent driving connections between the shaft and driving discs, each of said independent connections being such that relative rotation between a disc and the shaft causes relative axial movement between them whereby, in response to operation of the motor after operation of said independent disc moving means, each driving disc is urged against the driven disc with pressure sufficient for driving engagement, and whereby, when the engine becomes self-operative, the driving pressure will be relieved.

4. In an engine starter, the combination of a driven disc connected with the engine, driving discs located respectively on opposite sides of the driven disc, a starting motor, a shaft driven by the motor, means independent of the motor for moving the driving discs against the driven disc prior to operation of the motor, and independent driving connections between the shaft and driving discs, said independent connections being screw-threads, respectively, of opposite pitch whereby, in response to operation of the motor after operation of said independent disc moving means, each driving disc is urged against the driven disc with pressure sufficient for driving engagement, and whereby, when the engine becomes self-operative, the driving pressure will be relieved.

5. In an engine starter, the combination of a driven disc connected with the engine, driving discs located respectively on opposite sides of the driven disc, a starting motor, a shaft driven by the motor, independent driving connections between the shaft and driving discs so constructed and arranged that relative rotation between a disc and the shaft causes relative axial movement between them, and means independent of the motor for moving one of the driving discs axially into engagement with the driven disc and for causing the other driving disc to rotate in such direction relative to the shaft that said other driving disc will be moved axially against the driven disc.

6. In an engine starter, the combination of a driven disc connected with the engine, driving discs located respectively on opposite sides of the driven disc, a starting motor, a shaft driven by the motor, independent driving connections between the shaft and driving discs so constructed and arranged that relative rotation between a disc and the shaft causes relative axial movement between them, and means independent of the motor for moving the shaft axially thereby moving one of the driving discs axially into engagement with the driven disc and for causing the other driving disc to rotate in such direction relative to the shaft that said other driving disc will be moved axially against the driven disc.

7. In an engine starter, the combination of a driven disc connected with the engine, driving discs located respectively on opposite sides of the driven disc, a starting motor, a shaft driven by the motor, independent driving connections between the shaft and driving discs so constructed

and arranged that relative rotation between a disc and the shaft causes relative axial movement between them, and means independent of the motor for moving one of the driving discs axially into engagement with the driven disc, said means including a shifter sleeve having a helical spline connection with the other driving disc for causing said other disc to rotate in such direction relative to the shaft that said other driving disc will be moved axially against the driven disc.

8. In an engine starter, the combination of a driven disc connected with the engine, driving discs located respectively on opposite sides of the driven disc, a starting motor, a main shaft driven by the motor, a tubular shaft mounted on the main shaft and having a longitudinal-spline connection therewith, a spring urging the tubular shaft in one direction against a stop, driving discs each mounted on the tubular shaft and having a screw-thread connection therewith, a shifter sleeve having a helical spline connection with one of the driving discs and a longitudinal spline connection with the tubular shaft, a spring urging said sleeve into a certain position relative to the driving disc with which it is associated, and means for moving the sleeve.

9. In an engine starter, the combination of a driven disc connected with the engine, driving discs located respectively on opposite sides of the driven disc, a starting motor, a shaft driven by the motor, means independent of the motor for moving the driving discs against the driven disc with yielding pressure prior to operation of the motor, and independent driving connections between the shaft and driving discs, said connections each including camming members whereby, in response to operation of the motor after operation of said independent disc moving means, each driving disc is urged against the driven disc with pressure sufficient for driving engagement, and whereby, when the engine becomes self-operative, the driving pressure will be relieved.

10. In an engine starter, the combination of a driven disc connected with the engine, driving discs located respectively on opposite sides of the driven disc, a starting motor, a shaft driven by the motor, means independent of the motor including yielding motion transmitting provisions for moving the driving discs against the driven disc prior to operation of the motor, and independent driving connections between the shaft and driving discs, each of said independent connections being so constructed and arranged that, in response to operation of the motor after operation of said independent disc moving means, the pressure between each driving disc and the driven disc will be increased and that said pressure will be relieved when the engine becomes self-operative.

11. In an engine starter, the combination of a driven disc connected with the engine, driving discs located respectively on opposite sides of the driven disc, a starting motor, a shaft driven by the motor, means independent of the motor including yielding motion transmitting provisions for moving the driving discs against the driven disc prior to operation of the motor, and independent driving connections between the shaft and driving discs, each of said independent connections being such that relative rotation between a disc and the shaft causes relative axial movement between them whereby, in response to operation of the motor after operation of said independent disc moving means, each driving disc is urged against the driven disc with pressure

sufficient for driving engagement, and whereby, when the engine becomes self-operative, the driving pressure will be relieved.

12. In an engine starter, the combination of a driven disc connected with the engine, driving discs located respectively on opposite sides of the driven disc, a starting motor, a shaft driven by the motor, means independent of the motor for moving the driving discs against the driven disc with yielding pressure prior to operation of the motor, and independent driving connections between the shaft and driving discs, said independent connections being screw-threads, respectively, of opposite pitch whereby, in response to operation of the motor after operation of said independent disc moving means, each driving disc is urged against the driven disc with pressure sufficient for driving engagement, and whereby, when the engine becomes self-operative, the driving pressure will be relieved.

13. In an engine starter, the combination of a driven disc connected with the engine, driving discs located respectively on opposite sides of the driven disc, a starting motor, a shaft driven by the motor, independent driving connections between the shaft and driving discs so constructed and arranged that relative rotation between a disc and the shaft causes relative axial movement between them, and means independent of the motor including yielding motion transmitting provisions for moving one of the driving discs axially into engagement with the driven disc and for causing the other driving disc to rotate in such direction relative to the shaft that said other driving disc will be moved axially against the driven disc.

14. In an engine starter, the combination of a driven disc connected with the engine, driving discs located respectively on opposite sides of the driven disc, a starting motor, a shaft driven by the motor, independent driving connections between the shaft and driving discs so constructed and arranged that relative rotation between a disc and the shaft causes relative axial movement between them, and means independent of the motor including yielding motion transmitting provisions for moving the shaft axially thereby moving one of the driving discs axially into engagement with the driven disc and for causing the other driving disc to rotate in such direction relative to the shaft that said other driving disc will be moved axially against the driven disc.

15. In an engine starter, the combination of a driven disc connected with the engine, driving discs located respectively on opposite sides of the driven disc, a starting motor, a shaft driven by the motor, independent driving connections between the shaft and driving discs so constructed and arranged that relative rotation between a disc and the shaft causes relative axial movement between them, and means independent of the motor including yielding motion transmitting provisions for moving one of the driving discs axially into engagement with the driven disc, said means including a shifter sleeve having a helical spline connection with the other driving disc for causing said other disc to rotate in such direction relative to the shaft that said other driving disc will be moved axially against the driven disc.

16. In an engine starter, the combination of a driven disc connected with the engine, driving discs located respectively on opposite sides of the driven disc, a starting motor, a main shaft

driven by the motor, a tubular shaft mounted on the main shaft and having a longitudinal spline connection therewith, a spring urging the tubular shaft in one direction against a stop, 5 driving discs each mounted on the tubular shaft and having a screw-thread connection therewith, a shifter sleeve having a helical spline connection with one of the driving discs and a longitudinal spline connection with the tubular shaft, a 10 spring urging said sleeve into a certain position relative to the driving disc with which it is associated, and means including yielding motion transmitting provisions for actuating the shifter sleeve.

15. 17. For use in a starter for an engine having a friction driven disc, the combination of a shaft adapted to be connected with a starting motor and to be driven thereby, friction driving discs mounted upon said shaft and adapted to engage 20 with opposite sides of the driven disc of the engine, independent driving connections between the shaft and driving discs, said connections each including camming members whereby, in response to operation of the motor following preliminary 25 movement of the driving discs into engagement with the engine disc, each driving disc is urged against the engine disc with pressure sufficient for driving engagement, and whereby, when the engine becomes self-operative, the driving pressure 30 sure will be relieved, and driving disc shifting means adapted for actuation independent of the motor and including a member, supported by the shaft and movable longitudinally thereof and provisions responsive to movement of said 35 member in one direction for causing preliminary movement of said driving discs into engagement with the engine discs.

18. For use in a starter for an engine having a friction driven disc, the combination of a shaft 40 adapted to be connected with a starting motor and to be driven thereby, friction driving discs mounted upon said shaft and adapted to engage with opposite sides of the driven disc of the engine, independent screw-thread connections of 45 opposite pitch, respectively, between the shaft and driving discs, and driving disc shifting means adapted for actuation independent of the motor and including a member, supported by the shaft and movable longitudinally thereof and provisions responsive to movement of said member 50 in one direction for causing preliminary movement of said driving discs into engagement with the engine disc.

19. For use in a starter for an engine having a friction driven disc, the combination of a shaft 55 adapted to be connected with a starting motor and to be driven thereby, friction driving discs mounted upon said shaft and adapted to engage with opposite sides of the driven disc of the engine, independent screw-thread connections of opposite pitch, respectively, between the shaft and driving discs, a shifter sleeve carried by the shaft and having a helical spline connection with one of the driving discs and a longitudinal spline 60 connection with the shaft, and a spring urging said sleeve into a certain position relative to the driving disc with which it is associated.

20. For use in a starter for an engine having a friction driven disc, the combination of a shaft 65 adapted to be connected with a starting motor and to be driven thereby, friction driving discs mounted upon said shaft and adapted to engage with opposite sides of the driven disc of the engine, independent driving connections between the shaft and driving discs, each of said independent con-

nnections being such that relative rotation between a disc and the shaft causes relative axial movement between them whereby, in response to operation of the motor after operation of said independent disc moving means, each driving disc is urged 5 against the driven disc with pressure sufficient for driving engagement, and whereby, when the engine becomes self-operative, the driving pressure will be relieved, a shifter sleeve carried by the shaft and having a helical spline connection 10 with one of the driving discs and a longitudinal spline connection with the shaft, and a spring urging said sleeve into a certain position relative to the driving disc with which it is associated.

21. An engine starter drive adapted to be operated by a starting motor having a rotatable shaft, and comprising a driven disc connected to the engine to be started, driving discs located on opposite sides of the driven disc, and adapted to be moved into engagement with the driven disc, 20 means for moving said driving discs into engagement with said driven disc prior to operation of the motor, said driving discs having cam surfaces formed thereon adapted to be operated by cooperating cam members driven by the motor shaft 25 whereby, in response to operation of the motor after the aforementioned preliminary movement of the driving discs, each driving disc is urged against the driven disc with pressure sufficient for driving engagement, and whereby when the engine 30 becomes self-operative, the pressure will be relieved.

22. An engine starter drive adapted to be operated by a starting motor having a rotatable shaft, and comprising a driven disc connected to 35 the engine to be started, driving discs located on opposite sides of the driven disc, and adapted to be moved into engagement with the driven disc, means for moving said driving discs into engagement with said driven disc prior to operation of 40 the motor, said driving discs having cam surfaces formed thereon adapted to be operated independently by other cam members driven by the motor shaft, the cooperating cam members being so constructed and arranged that, in response to operation of the motor after the aforementioned preliminary movement of the driving discs, the pressure of said driving discs against the driven discs 45 will be increased and that said pressure will be relieved when the engine becomes self-operative. 50

23. An engine starter drive adapted to be operated by a starting motor having a rotatable shaft, and comprising a driven disc connected to the engine to be started, driving discs located on opposite sides of the driven disc, and adapted to 55 be moved into engagement with the driven disc, means for moving said driving discs into engagement with said driven disc prior to operation of the motor, said driving discs each being provided with screw threads adapted to cooperate 60 with other screw threads rotatable by the motor shaft, said screw threads on the driving discs being of opposite pitch, whereby in response to rotation of the motor shaft after the above mentioned preliminary movement of the driving discs, each 65 driving disc is urged against the driven disc with pressure sufficient for driving engagement, and whereby when the engine becomes self-operative the pressure will be relieved.

24. An engine starter drive adapted to be operated by a starting motor having a rotatable shaft, and comprising a driven disc connected to the engine to be started, driving discs located on opposite sides of the driven disc, a tubular shaft adapted to be splined to the motor shaft to be 70 75

driven thereby, a spring urging said tubular shaft in one direction against a stop, said driving discs being each mounted on the tubular shaft and having a screw thread connection therewith, a shifter sleeve having a helical spline connection with one of the driving discs and a longitudinal spline connection with the tubular shaft, and adapted when moved from its normal position to effect engagement of the driving discs with the driven disc, and

5 a spring for normally holding the shifter sleeve in its normal position.

10 25. An engine starter drive adapted to be operated by a starting motor having a rotatable shaft, and comprising a driven disc connected to

the engine to be started, driving discs located on opposite sides of the driven disc, driving means for the driving discs adapted to be operated by the motor shaft and so constructed that rotation of each disc relative to the shaft causes axial movement between the disc and shaft, and a shifter member operable, when shifted, to move one of the driving discs axially into engagement with the driven disc and to cause the other driving disc to rotate in such direction relative to the shaft that said other driving disc will be moved axially against the driven disc.

JOHN B. DYER.
